UNITED STATES PATENT OFFICE.

WILLIAM WILLIAMS, OF HOPKINSVILLE, KENTUCKY.

STERILIZING ATTACHMENT FOR THE MOUTHPIECES OF SPEAKING INSTRUMENTS.

944,397.

Specification of Letters Patent. Patented Dec. 28, 1909.

Application filed May 10, 1909. Serial No. 494,948.

To all whom it may concern:

Be it known that I, WILLIAM WILLIAMS, a citizen of the United States, residing at Hopkinsville, in the county of Christian, State of Kentucky, have invented certain new and useful Improvements in Sterilizing Attachments for the Mouthpieces of Speaking Instruments; and I do hereby declare the following to be a full, clear, and exact 10 description of the invention, such as will enable others skilled in the art to which it appertains to make and use the same.

This invention relates to improvements in attachments for the mouth pieces of speaking instruments and is particularly adapted for use in connection with the mouth piece or transmitter of a telephone.

It has for its object the provision of an attachment which is adapted to be readily 15 clamped to most forms of telephone mouth pieces now in use and when so positioned will operate to maintain the said mouth piece in a sanitary condition.

Another object is the provision of an improved form of tube which contains the disinfecting substance so arranged that the latter will be distributed on the inner face 20 of the mouth piece and further designed to offer no resistance to the sound waves passing to the diaphragm.

A further object is the provision of an improved form of cap or closure for the open end of the mouth piece which is designed to prevent the entrance of dust or 25 other foreign matter therein.

With these and other objects in view as will more fully hereinafter appear, the present invention consists in certain novel details of construction and arrangement of 30 parts, hereinafter fully described, illustrated in the accompanying drawings and more particularly pointed out in the appended claims, it being understood that various changes in the form, proportion, size and 35 minor details of the device may be made without departing from the spirit or sacrificing any of the advantages of the invention.

In the accompanying drawings forming 40 part of the specification:—Figure 1 is a front elevation of a telephone showing my improved device applied to the mouth piece thereof. Fig. 2 is a detailed side elevation 45 of the device. Fig. 3 is a rear end view thereof. Fig. 4 is a longitudinal sectional view.

Similar numerals of reference are employed to designate corresponding parts throughout.

As shown in the drawings the casing of 50 the telephone and its parts are designated in general by the numeral 5, with the standard of the mouth piece which is shown at 6. This latter member is of the usual construction and is substantially bell-shaped in 55 contour.

What will subsequently be termed a cap is designated in general by the numeral 7. This member is slightly greater in diameter than the outer end of the mouth piece and 60 is designed to completely close the same when applied as shown in Fig. 1. The cap may be formed of any suitable material and is provided with a centrally disposed and substantially frusto-conical depression 8, 65 while a portion adjacent the periphery of the cap is turned laterally so as to provide a flange 9 which is disposed on the same face of the cap as the projection formed by the depression. The periphery of the outer end 70 of the mouth piece engages the inner face of the flange so that the tightest possible joint is formed between the mouth piece and cap. The outer face of the flange is provided with a plurality of spaced openings through each 75 of which extends a clamp arm. The clamping 80 device may, if desired, be formed of a single piece of resilient wire or the like which is disposed on the inner face of the flange 9 and at certain intervals is formed 85 into loops 10 which are extended through the openings of the flange and then curved over the outer face of the flange and are directed inwardly as shown at 11 on a curved line so as to conform to the curvature of the 90 outer face of the mouth piece. It is to be understood, however, that I am not to be limited to this specific form of clamping 95 arm since it can be readily seen that each clamping arm might be formed of a single 100 piece of resilient wire or the like, the opposite terminals of which could be inserted through the openings in the flange and clenched against the inner face thereof. The 105 inwardly extending projection formed by the depression 8 will, when the parts are in position, extend for a short distance in the mouth piece and the central portion of this depression is provided with an annular opening to receive the disinfecting tube.

The tube 11' may be of any suitable material and is of a diameter to snugly fit with

in the opening of the cap and may be further secured therein by means of packing or the like. The opposite ends of the tube extend for equal distances beyond the opposite faces of the central portion of the depression 8, and the upper end terminates in an annular flange 12 or the like. The outer face of this flange is provided with a screw thread which receives the threaded end of a hollow body 13. The latter is substantially paraboloidal in vertical section and adjacent its base is provided with a plurality of spaced annular openings 14 which are disposed above the plane of the flange 12. The opposite end of the tube 11' or that disposed within the mouth piece or transmitter is provided with a hollow bulb shaped cup 15, the diameter of which is slightly greater than that of the tube. The open end of the bulb 15 is threaded and adapted to receive the inner end of the tube 11', while the greater portion of its surface in advance of the open end is provided with a plurality of perforations 16. The bulb contains a sponge or the like which is adapted to hold a slowly vaporizing anti-septic and may be interiorly provided with an annular flange 17 disposed between the open end and innermost circle of the openings 16 and which is adapted to support the sponge 18 between its face and the inner end of the tube 11'.

In the normal position of the parts as shown in Fig. 1 the bulb 16 will extend for a considerable distance into the tube of the mouth piece but not far enough to hamper the vibrations of the diaphragm while the outer end of the bottom will project slightly in advance of the plane of the cap. Thus it will be seen when the voice is directed into the depression 8 the sound will pass through the opening 14, tube 11', sponge 18 and out through the opening 16 to vibrate the diaphragm in the usual manner.

It has been found in practice that the provision of the sponge and its contents will in no way detract from the usefulness of the telephone. It can be seen in the use of the device that the currents of air passing through the sponge 18 will diffuse the vapor and disinfectant throughout the inner surface of the mouth piece.

The utility of the device will be readily

appreciated since it is well known that the mouth pieces of telephones and more particularly those at public stations have been known to spread numerous diseases among the users. It can be seen with a device of this kind that all disease germ life will be eradicated from the mouth piece and from the outer face of the cap by reason of the fumes of the disinfectant.

Having thus described my invention what is claimed as new, is:—

1: In a disinfecting attachment for the mouth piece of a speaking instrument, the combination with a cap forming a closure for the mouth piece and having a peripheral perforated flange to bear on the outer edge of the mouth piece and a wire fastener bent upon itself and extended through the perforations of the flange, to provide clamp arms to bear on the outer face of the mouth piece.

2. In a disinfecting attachment for the mouth piece of a speaking instrument, a closure cap having a tube, one end of which is disposed within the mouth piece and the opposite end provided with openings and extending beyond the plane of the cap.

3. In a disinfecting attachment for the mouth piece of a speaking instrument a tube provided at one end with a perforated bulb containing a disinfecting substance and provided at its outer end with a perforated button.

4. In a disinfecting attachment for the mouth piece of a speaking instrument, a tube having a perforated bulb on one end interiorly provided with a disinfecting substance and provided at its opposite end with an oblong button having openings adjacent said tube.

5. In a disinfecting attachment for the mouth piece of a speaking instrument a tube provided at one end with a perforated bulb containing a disinfecting substance, a perforated button at the opposite end of, said tube and a closure plate disposed between said bulb and button.

In testimony whereof, I affix my signature, in presence of two witnesses.

WILLIAM WILLIAMS.
